(57) **CLAIM**

The ornamental design for a cigarette lighter top with extendable and rotatable tip, as shown and described.

DESCRIPTION

FIG. 1 is a front-left isometric view of a cigarette lighter top with extendable and rotatable tip embodying our new design; FIG. 2 is a rear-right perspective view of FIG. 1; FIG. 3 is a left side elevation view of FIG. 1; FIG. 4 is a right side elevation view of FIG. 1; FIG. 5 is a front side elevation view of FIG. 1; FIG. 6 is a rear side elevation view of FIG. 1; FIG. 7 is a top plan view of FIG. 1; FIG. 8 is a bottom plan view of FIG. 1; FIG. 9 is a front-left isometric view similar to FIG. 1, now illustrating an alternate position of the cigarette lighter top with extendable and rotatable tip; FIG. 10 is a rear-right perspective view of FIG. 9; FIG. 11 is a left side elevation view of FIG. 9; FIG. 12 is a right side elevation view of FIG. 9; FIG. 13 is a front side elevation view of FIG. 9; FIG. 14 is a rear side elevation view of FIG. 9; FIG. 15 is a top plan view of FIG. 9; and, FIG. 16 is a bottom plan view of FIG. 9.

The broken lines are for illustration only and form no part of the claimed design.
